UNITED STATES PATENT OFFICE.

JOHN ENRIGHT, OF LOUISVILLE, KENTUCKY, ASSIGNOR TO HIMSELF AND
JAMES R. DEL VECCHIO, OF SAME PLACE.

IMPROVEMENT IN PASSENGER-REGISTERS.

Specification forming part of Letters Patent No. 79,060, dated June 23, 1868.

To all whom it may concern:

Be it known that I, JOHN ENRIGHT, of Louisville, in the county of Jefferson and State of Kentucky, have invented a new and useful Improvement in Passenger-Registers; and I do hereby declare that the following is a full, clear, and exact description thereof, which will enable those skilled in the art to make and use the same, reference being had to the accompanying drawings, forming part of this specification, in which—

Figure 1 is a partial front view of the registering device. Fig. 2 is a vertical section of the same. Fig. 3 is a detail section of the same, taken through the line *xx*, Fig. 2. Fig. 4 is a detail view of the registering device, the dial-plate and part of the frame being removed. Fig. 5 is a detail sectional view of the same, taken through the line *yy*, Fig. 4. Fig. 6 is a detail under-side view of a portion of the same.

Similar letters of reference indicate corresponding parts.

My invention has for its object to furnish an improved apparatus for registering the number of passengers or persons entering street-cars, ferry-boats, and other places, which shall be so constructed and arranged as to register said passengers accurately, and, at the same time, so that it cannot be falsified or made to register an incorrect number without breaking the apparatus, and thus showing that it has been tampered with.

A represents the platform of a car, the deck of a boat, or floor of any room or place the number of persons entering into which it is desired to register.

B is a vertical shaft passing down through the deck or floor *A*, and the lower end of which is pivoted to the box or plate *C*, attached to the bottom or lower side of the floor *A*, and the upper end of which works in a socket attached to the box or casing *D*, as shown in Fig. 2.

If desired, the shaft *B* may be further secured by braces *E*, the lower ends of which are attached to the floor *A*, and their upper ends are attached to or secured in place by a collar or collars upon the shaft *B*, as shown in Fig. 2.

To the shaft *B* are attached four radial

doors, *F*. The number of doors or gates *F* may be more or less than four, and they should be so arranged that only one person can be received between two adjacent doors.

The doors *F* may be radial arms, as shown in Figs. 2 and 3, or they may be made longer, so as to extend to or nearly to the floor or platform *A*. In the latter case the braces *E* must be omitted, and the shaft *B* sufficiently secured at its ends.

To the lower end of the shaft *B*, beneath the floor *A*, is attached a series of radial arms, *G*, equal in number to the doors *F*, and so arranged that each of the arms *G* may be midway between two of the doors *F*, as shown in Fig. 3.

H is a spring attached to the plate or box *C* in such a position as to press against the ends of two adjacent arms, *G*, and bring the shaft to rest after the admission of each passenger in such a position as to close the entrance. Then, as the door *F* is pushed before the passenger in entering, the arm *G* pushes back the spring *H*, which immediately springs forward to again stop the shaft *B*.

To the end of each of the arms *G* is pivoted a friction-wheel, *I*, to diminish the friction between the ends of the said arms *G* and the said spring *H*.

To the upper sides of the arms *G*, near their ends, are attached pins *g'*, or their equivalents, which strike against the pawl *J* to operate the registering device.

The box or casing *D*, which incloses all the space in which the doors *F* work, except that part through which the passenger passes in entering the car, boat, or room, may be made semicircular in form, as shown in Figs. 2 and 3, or it may be made polygonal in form, as may be desired.

K is a guard attached to the side of the entrance opposite to the box or casing *D*, and which is curved to correspond with the sweep of the outer ends or edges of the doors *F*, to guard against any passenger squeezing past said doors without operating the register.

It should be observed that the box or casing *D* should be so firmly secured to the platform or floor *A* that it cannot be pushed or moved out of its place by the crowding and pushing of persons wishing to enter.

L is a bent lever pivoted to the plate or box C, and to one of the arms, l', of which is pivoted the pawl J, against which the pins g', attached to the arms G, strike when the shaft B is revolved by a person passing in or out.

One end of the pawl J is held out by a coiled or other spring, M, so that the pins g' may strike it and operate the lever L upon the entrance of each passenger. The other end of the pawl J is so formed that when the shaft B is revolved by a person passing out the pins g' may strike it, compress the spring M, and pass by without operating the lever L.

The arm l' of the lever L is so formed that when the said lever is operated by the pins g' striking the pawl J the end of the said arm l' may be moved forward into such a position that, should the lever be held in that position by any person or thing and another person attempt to enter before the said lever has returned to its former position, the pin of the next arm, G, would strike against the end of the said arm l', and thus prevent the revolution of the shaft B, and, consequently, the entrance of the person.

N is a stop-pin attached to the plate or box C in an angle of the lever L, to limit the movement of said lever, and thus guard against its ever getting out of place.

O is a bell-crank pivoted to the plate or box C, or to a bracket or other support attached to said box or plate C, or to the lower side of the floor or platform A. One arm of the bell-crank O is connected with the bent lever L by a wire, P, or its equivalent. The connecting-wire P may, if desired, be replaced with a connecting-rod, the ends of which are pivoted to the bell-crank O and to the lever L.

It should be observed that the parts of the apparatus most subject to friction, and consequently most liable to wear, should be made of hardened steel or other metal not easily worn, so that said parts may not become so worn by continuous use as not to operate properly. To the other arm of the bell-crank O is attached the end of a connecting-wire, Q, the other end of which is connected to the arm or lever R, pivoted to the shaft S, working in bearings in the box or case T. The box or case T is provided with a door, t', which may be locked.

In some situations I prefer to insert a glass plate, U, in the door t', and in other places I prefer to use the said door without the said glass plate.

V is a wheel attached to the shaft S, and which is made with exactly a hundred teeth. The wheel V is moved forward by the pawl W, pivoted to the arm or lever R, and which is held forward against the teeth of the wheel V by the spring X, one end of which is attached to the arm R, and the other end of which presses against the said pawl W.

The movement of the arm or lever R is limited by the length of the slot in the side of the case or box T, so that the said arm or lever R can only be moved far enough to revolve the

wheel V the hundredth part of a revolution, or through the space of one tooth.

The lever or arm R and pawl w are moved back, after operating the wheel V, by the coiled or other spring Z, attached to the box, or case T, and connected with the arm r' of the lever or arm R, or directly with said lever.

The wheel V is kept from being carried back by the pawl w, and is held steady by the spring-pawl A', adjustably secured to the box or case T by a screw or screws passing through a slot in said pawl, as shown in Fig. 4.

B' is a toothed segment attached to the shaft C', which works in bearings in the bottom of the box or case T and in the top plate, D', of said box or case, as shown in Fig. 5. The number of teeth in the segment B' is immaterial, and said segment may be extended into a circle, if desired, the box or case T being enlarged accordingly. The segment or wheel B', when made a complete wheel, should be arranged so that the outer end of its shaft may come through the dial inside of the units-scale. In this case it is necessary to use a bracket with a bearing, in which the inner end of the shaft could revolve. The outer end works in a bearing in the outer plate. The bracket may be made fast to the outer plate by holes in its ends. It is also necessary to have a hole through the large finger, so that when it points at the zero the key can be passed through said finger to the end of the shaft when necessary to move the little finger to the zero on the hundreds-scale, and the large finger should also be bent outward, so as to clear the end of the shaft. The bracket should be arranged in position so as not to rub the wheel V or allow the shaft of the wheel B' to rub it.

Considering the jarring or surging of street-cars, I prefer a complete wheel instead of a segment, as it will be better balanced upon the shaft, and therefore less liable to be jolted from its place.

Upon the shaft S is formed a single tooth, E', which, upon each revolution of the wheel V, moves the segment B' forward one tooth, so that the wheel V registers the units and tens, and the segment B' registers the hundreds and thousands.

F' are springs attached to the under side of the plate D', which press against the teeth of the segment B' and hold it stationary, except when operated upon by the tooth or cog E'.

G' is an index-finger attached to the shaft S, and which points to the division-marks of the scale formed upon the dial-plate H', to indicate the number registered up to a hundred.

To the side of the segment B' is rigidly attached a short arm, which projects through a circular slot in the dial-plate H', and to the projecting end of which is attached a small index-finger, I', which points to the division-marks of a scale formed upon the dial-plate H' at the side of the circular slot through said dial-plate, to indicate the hundreds and thousands registered.

If desired, the segment B' may be extended into a wheel, and may have a single tooth formed upon its hub, meshing into and operating a third wheel or segment registering the tens and hundreds of thousands; but this third wheel or segment will seldom or never be required.

To the outer end of the arm or lever R is connected the lower end of the connecting wire or rod J' in such a way that pushing or pulling said rod or wire J' downward will not operate the lever or arm R.

The upper end of the wire or rod J' is connected with the hammer of the bell or gong K' in such a way that the entrance of each passenger will not only move the index-finger to make the register, but will also sound the bell or gong, thus giving notice that a passenger has entered the car, boat, or room to which the apparatus has been attached.

I claim as new and desire to secure by Letters Patent—

1. The combination of the doors or bars F, shaft B, radial arms G, having stop-pins g', or their equivalent, attached to them, spring-pawl J, and bent lever L with each other when placed at the entrance of a car, boat, room, or other place, substantially as herein shown and described, and for the purpose set forth.

2. In combination with the above and with each other, I claim the toothed wheel V, attached to a shaft, S, having a single tooth or cog, E', formed upon it and carrying an index-finger, G', the toothed segment or wheel E', carrying an index-finger, I', the dial-plate H', lever or arm R, pawls W and A', connection P, lever O, rod J, and gong K', all arranged and operating as set forth, for the purpose specified.

JOHN ENRIGHT.
